UNITED STATES PATENT OFFICE.

GEORGE CLAUSS, JR., OF ELIZABETH, AND ALBERT M. SCHOMBURG, OF NEWARK, NEW JERSEY.

BOTTLE-FILLING MACHINE.

SPECIFICATION forming part of Letters Patent No. 531,717, dated January 1, 1895.

Application filed April 19, 1894. Serial No. 508,177. (No model.)

To all whom it may concern:

Be it known that we, GEORGE CLAUSS, Jr., of Elizabeth, Union county, and ALBERT M. SCHOMBURG, of Newark, county of Essex, New Jersey, have invented certain new and useful Improvements in Bottle-Filling Machines, of which the following is a specification.

The invention relates to bottle filling machines such as shown and described in the Letters Patent of the United States, No. 482,894, granted to us under date of September 20, 1892.

The object of the present invention is to provide a new and improved bottle filling machine arranged in such a manner as to insure the proper filling of bottles with beer or other liquids and without waste of the liquid.

The invention consists in various parts and details and combinations of the same, as hereinafter more fully described, and pointed out in the claims.

Reference is to be had to the accompanying drawings, forming a part of this specification, and in which similar letters of reference indicate corresponding parts in all the views.

Figure 1 is a sectional front elevation of the improvement. Fig. 2 is an enlarged sectional elevation of a bottle and the filling device therefor. Fig. 3 is an enlarged sectional plan view of the filling device on the line 3. 3. of Fig. 2, and Fig. 4 is an enlarged sectional side elevation of one of the float valves.

The improved bottle filling machine is provided with a number of posts A on which is held adjustably a platform B adapted to receive a tray C carrying the bottles D to be filled, the said platform and tray being similar in construction as the ones shown and described in the Letters Patent above referred to so that further description of the same is not deemed necessary.

In the platform B are fitted to slide the vertically extending guide rods E supporting at their upper ends the tank F adapted to contain the liquid to be filled into the bottles on the tray C, the said tank being provided with suitable means for filling it and with devices for raising and lowering the tank. The latter is properly counterbalanced by ropes or chains E' and connected with the lower ends of the guide-rods and passing over pulleys E² journaled in brackets on the underside of the

platform B; the said ropes or chains supporting a suitable counterbalancing weight E³.

In the bottom of the tank F are secured the filling pipes by extending down through bearings in the guide-plate A' adjustably secured to the upper ends of the posts A. The filling pipes G are adapted to pass into the bottles D arranged in alignment with the pipes and supported on the tray C. The upper end of each filling pipe is formed with a valve seat G' adapted to be engaged by a weighted valve H held on a rod H' extending downward through the corresponding filling pipe. The rods H' are of such length relative to the filling pipes G that when the several parts are in the position shown in Fig. 1 and the valves H are seated on their seats G' then the extreme lower ends of the rods project a suitable distance below the lower ends of the filling pipes G. Now when the tank F is lowered the filling pipes G pass into the bottles and the projecting ends of the rods H' finally strike the bottoms of the bottles so on a further downward movement of the said tank F the rods H are held stationary and the valves H' are unseated to permit the liquid to flow from the tank F through the filling pipes G into the several bottles D.

In order to permit a proper escape of the air contained in the bottles D on filling the same with the liquid, the following device is provided: On each filling pipe G is held loosely a short tube I having an interior diameter somewhat more than the corresponding filling pipe so that passage is formed between the filling pipe G and its surrounding tube I. Near the lower end of each tube I is secured or formed a flange I² on the under side of which abuts a ring I' made of rubber or other suitable material and adapted to be seated in the mouth of the bottle as is plainly shown in Fig. 2. On the upper end of each tube I is secured a head J formed with the chamber J' connected by the port J² with the interior of the tube G and into the said chamber J' extends the lower end of a vertically disposed float valve K held loosely in the reduced extension chamber J³ formed in its top with a valve seat J⁴ opening to the outside and adapted to be closed at the inside of the extension chamber J³ by the valve K' screwed or

otherwise secured in the end of the hollow float valve K as plainly shown in Fig. 4. An indicating stem K² extends upwardly from the valve K' and passes loosely through the valve seat J⁴ to indicate the position of the valve K' relative to its seat J⁴. In the side wall of the hollow float valve K are arranged vertically disposed grooves K³ to facilitate the escape of the air from the chamber J' through extension chamber J³ and seat J⁴.

A spring L is coiled near the upper end of each filling pipe G, the lower end of each spring resting on the head J while the upper end is adapted to be engaged by the under side of the tank F on lowering the same as shown in Fig. 2 to compress the spring and to press the head J and its tube I downward to firmly seat the ring I' on the mouth of the bottle.

In the head J above the tube I is arranged a suitable packing J⁵ fitting on the filling pipe G so as to hold the tube I in proper place by frictional contact with the filling pipe after the tension of the spring is released on raising the tank F and at the time the spring is fully released and extended as shown in Fig. 1. The upward movement of the tubes I is limited on the return or upward movement of the tank F by the flange I² striking the under side of the guide plate A'.

On the guide rods E is fitted to slide loosely a centering plate N adapted to rest on pins E⁴ secured on the guide rods at the time the tank F and its guide rods are in an uppermost position as shown in Fig. 1. On the under side of the centering plate N are arranged centering heads N' having conical openings for the central passage of the filling pipes the said heads being adapted to fit into the exterior surface of the mouths of the bottles so as to move the same into a central position for the ready entrance of the filling pipes G at the time the tank F is lowered.

The operation is as follows: When the several parts are in the position shown in Fig. 1 and the tank F is filled with liquid and a tray C with empty bottles is on the platform B then the operator in order to fill the bottles with the liquid contained in the said tank F moves the latter downward whereby the guide rods move in the same direction and the centering plate N moves with its heads N' over the mouths of the bottles to properly center the same for the following filling pipes G and 55 the rings I'. The latter on the further downward movement of the tank filling pipes and tubes I finally seat themselves in the mouths of the bottles so that a further downward motion of the tubes I is prevented and the 60 tubes are held stationary. The filling pipes G move downward into the bottles on the further lowering of the tank, the said pipes now sliding through the tubes I and their heads J and as the springs L rest on the said heads J the downward moving tank finally 65 engages the springs and compresses the same whereby the tubes are pressed and their flexi-

ble rings finally seated in the mouths of the bottles as will be readily understood by reference to Fig. 2. When the tank F is finally moving into its lowermost position then the rods H strike the bottoms of the bottles and the valves H' are unseated to permit the liquid to flow through the filling pipes into the bottles to fill the same as previously described. When the liquid flows into the bottles the air therein retreats and passes upward through the tubes I, port J², chambers J' J³ and open valve seat J⁴ to the outer air. When the inflowing liquid has finally filled the bottles it rises in the tubes I and passes through the ports J² into the chambers J' in which the rising liquid lifts the float valves K so that the valves K' seat themselves on the seats J⁴ thus preventing any outflow of the liquid at the heads J and at the same time stopping further inflow of the liquid into the bottles through the filling pipes G. As the float valves rise the stems K² move upward thus giving a signal to the operator that the bottles are filled. Now when all the stems K have moved into their uppermost position then the operator knows that the flow of the liquid through the filling pipes has ceased and he now raises the tank F and filling pipes G whereby the valves H' seat themselves to close the filling pipes at their upper ends. As the filling pipes recede out of the bottles the small amount of liquid in the filling pipes and in the tubes I and heads J flow back into the bottles to take the place of the space occupied by the lower part of the filling pipes that had extended into the bottles. By this arrangement the bottles are filled close up to the necks and no liquid whatever is wasted. On the return or upward movement of the tank the springs L are released so that the tubes I finally move with the filling pipes G owing to the frictional contact of the packings J⁵ with the said filling pipes. The pins E⁴ finally engage the centering plate N so as to lift the same clear off the bottles as shown in Fig. 1 to permit removal of the tray C containing the filled bottles.

Having thus described our invention, what we desire to secure by Letters Patent is—

1. In a bottle filling machine the combination with a filling pipe connected with a liquid supply and adapted to pass into the bottle to be filled of a tube fitted to slide on the said filling pipe and forming a space with the filling pipe for the passage of the air and liquid, the lower end of the said tube being adapted to be seated on the mouth of the bottle while the filling pipe slides down in the tube and into the bottle, a head held on the upper end of the said tube and provided with a chamber connected with the said space and having a valve seat and a float valve held in the said chamber and adapted to be seated on the valve seat in the said chamber substantially as shown and described.

2. In a bottle filling machine the combination with a filling pipe connected with a

liquid supply and adapted to pass into the bottle to be filled of a tube fitted to slide on the said filling pipe and forming a space with the filling pipe for the passage of the air and liquid, the lower end of the said tube being adapted to be seated on the mouth of the bottle while the filling pipe slides down in the tube and into the bottle, a head held on the upper end of the said tube and provided with a chamber connected with the said space and having a valve seat and a float valve held in the said chamber and adapted to be seated on the valve seat in the said chamber and a packing in the upper end of the said tube to connect the latter with the said filling pipe to permit the latter to carry the tube along when retreating from the bottle to move the tube out of engagement with the mouth of the bottle, substantially as shown and described.

3. In a bottle filling machine the combination with a tank mounted to slide, a filling pipe held in the bottom of the tank and a valve for opening and closing the said filling pipe,

of an air escaping and liquid retreating device comprising a tube in which slides the said filling pipe, and adapted to be seated on the mouth of the bottle a packing for holding the tube on the filling pipe, a head held on the upper end of the said tube and provided with a chamber containing a float valve, and a spring resting on the said head and adapted to be compressed by the said tank to hold the lower end of the tube on the mouth of the bottle and permit the filling pipe to slide in the tube on the further downward movement of the tank substantially as shown and described.

In testimony that we claim the foregoing as our invention, we have signed our names in presence of two witnesses, this the 16th day of April, 1894.

GEORGE CLAUSS, JR.
ALBERT M. SCHOMBURG.
